(57) **CLAIM**

The ornamental design for a tube adapter for liquid precision discharge machine, as shown and described.

DESCRIPTION

FIG. 1 is a front view thereof, showing a tube adapter for liquid precision discharge machine of my new design;

FIG. 2 is a right side view thereof;

FIG. 3 is a top plan view thereof;

FIG. 4 is a bottom plan view thereof;

FIG. 5 is a cross-sectional view of FIG. 3;

FIG. 6 is a cross-sectional view of FIG. 3;

FIG. 7 is a perspective view thereof;

FIG. 8 is another perspective view thereof;

FIG. 9 is a front view thereof, showing another embodiment of the tube adapter for liquid precision discharge machine of my new design;

FIG. 10 is a right side view thereof;

FIG. 11 is a top plan view thereof;

FIG. 12 is a bottom plan view thereof;

FIG. 13 is a cross-sectional view of FIG. 11;

FIG. 14 is a cross-sectional view of FIG. 11;

FIG. 15 is a perspective view thereof; and,

FIG. 16 is another perspective view thereof.

In the drawings, the broken lines depict portions of the tube adapter for liquid precision discharge machine that form no part of the claimed design.

1 Claim, 16 Drawing Sheets
